UNITED STATES PATENT OFFICE.

RASMUS R. HELLVIK AND PAUL SIPTROTT, OF NEW YORK, N. Y., ASSIGNEES TO METAL LAMP CORPORATION, A CORPORATION OF NEW YORK.

DESIGN FOR A COMBINED LAMP SHADE AND STAND.

Application filed May 23, 1924. Serial No. 9,694. Term of patent $3\frac{1}{2}$ years.

To all whom it may concern:

Be it known that we, RASMUS R. HELLVIK, a citizen of Norway, and PAUL SIPTROTT, a citizen of Germany, residing in New York city, N. Y., and doing business at 5 West 14th Street, New York, N. Y., have invented a new, original, and ornamental Design for Combined Lamp Shade and Stand, of which the following is a specification, reference being had to the accompanying drawing, forming part thereof.

The figure is a view of the combined lamp shade and stand in front elevation.

We claim:

The ornamental design for a combined lamp shade and stand as shown.

PAUL SIPTROTT. [L. S.]
RASMUS R. HELLVIK. [L. S.]
